VIAL ORIENTING AND TRAY LOADING MECHANISM

Frank J. Cozzoli, Plainfield, N. J.

Application July 6, 1953, Serial No. 366,357

10 Claims. (Cl. 226—14)

The present invention relates to vial processing machines and more particularly to a mechanism for removing vials for processing elements, for orienting the vials into positions for loading, and for leading them into suitable trays.

In its more specific aspects the invention concerns apparatus useful in removing vials from the jets of a washing machine in horizontal position then standing them upright and thereafter loading them into trays, all in cyclic steps in conformity with the operational cycle of the main machine, in this instance a vial washing machine.

The invention aims, for a primary objective, to avoid manual handling of the individual vials after they have been processed with cleansing agents. And to carry this objective further the invention is concerned with an efficient means automatically operative to place the vials in trays, untouched by hand, in upright position in readiness for subsequent processing operations.

Still another aim of the invention is to render available tray loading apparatus by the aid of which any size vial, within the range for which the main machine has been designed to handle, may be automatically removed from the washing jets, oriented to an upstanding position and loaded into a suitable tray.

The invention further proposes an improved structure and means for accomplishing the foregoing ends in a manner requiring a minimum of parts and mechanism subject to possible derangement by an inattentive or unskilled operator. As an additional safety measure the invention proposes an improved tray loading mechanism operative automatically to bring the main machine as well as the loading mechanism to a stand still in the event the operator fails to remove a fully loaded tray from the machine or, if and when removed, the operator fails to place an empty tray in proper receiving position on the machine.

For the purpose of explaining the nature of this invention reference will be made to washing machines of the general style and character of those illustrated in the patents to Cozzoli #2,604,896 and 2,555,875 which include essentially, an indexible endless conveyor provided with a plurality of banks of processing jets upon which the containers to be washed are initially placed and carried successively to and through a number of processing stations. The jets are loaded at one end of the machine and upon each operating cycle a bank of jets with vials telescoped thereon are presented at a delivery station. The present invention comprehends a variable stroke rake element adapted to engage the vials at the delivery station and to withdraw the vials from the jets and move them a distance not only sufficient to permit the empty jets to pass and a new lot to move into position but to move them along guided channels to an orienting station where they are caused to take an upright position.

2

tion. Thereafter, and in timed cycles, the vials are taken from the orienting station and channeled into the open end of a receiving tray placed at the end of the channel. Means are provided by which the main machine is stopped when a filled tray is removed from the machine or when a filled tray is not removed and the loading mechanism attempts to force more than the tray's complement of vials into the tray. In addition the invention proposes a means for adjusting the stroke 10 of the rake member so that relatively long or relatively short vials may arrive at the orienting station one group at a time, i. e., but one group of vials are presented to the orienting station in each index cycle of the main machine, and similarly but one group of vials are taken from the orienting station in each index cycle of the machine. These operations of withdrawing, orienting, and channeling of successive groups of vials are effected automatically and in timed sequence as will be explained.

By way of additional refinement the invention under- 20 takes to provide safety means operative to protect the machine from injury in the event a vial is misplaced and/or improperly comes through the processing machine. In such a case the receiving platform may yield and eject the faulty vial. Similarly means are provided for separating vials that may tend to stick together and additional means to prevent them from adhering to movable parts. By the aid of such safety measures the machine is rendered self-clearing and non-jamming.

Other objects and advantages will be in part indicated 30 in the following description and in part rendered apparent therefrom in connection with the annexed drawings.

To enable others skilled in the art so fully to apprehend the underlying features hereof that they may embody the same in the various ways contemplated by this 35 invention, drawings depicting a preferred typical construction have been annexed as a part of this disclosure and, in such drawings, like characters of reference denote corresponding parts throughout all the views, of which:

Figure 1 of the drawings is a side elevation of a portion 40 of a vial washing machine with which this invention is operatively associated.

Figure 2 is a detail view of a gate operating cam and cam follower. Figure 3 is a similar view of a vial pusher cam and its associated cam follower.

Figure 4 is a plan view of Figure 1 illustrating a bank 45 of jets in delivery position, a group of vials in their oriented position ready to be moved into the channel leading to the open end of a receiving tray.

Figure 5 is a view of part of the vial pusher carriage 50 in extended position.

Figure 6 is a schematic diagram of the drive and its electrical control circuit.

Referring more particularly to Figure 1 of the drawings the delivery end of a representative vial washing 55 machine has been illustrated. In this machine, or any machine with which the present invention may be combined, the vials are carried from one processing station to another on an endless conveyor that tracks sprockets at each end. In the instant machine the sprockets 10 are journaled in a main frame 11, and periodically indexed by means of a chain 12, Geneva star wheel 13, and crank 14, the latter being fast on a main drive shaft 15. The shaft 15 receives normally continuous rotary power from an electric motor (not shown), and drive 60 means including a chain and sprocket drive indicated at 16. Through the action of the Geneva mechanism, the various banks of vials V are moved successively through a prescribed number of washing stations and brought successively to a delivery station while assum-

ing a telescoped relation with the washing jets indicated at 17. Underlying the jets at the delivery station D, a slotted support 18 is positioned adapted to cradle the vials at the end of the movement afforded by the Geneva index mechanism. The slots 19 in the ends of the support 18 underlie the jets so that after the vials are removed, the jets may pass through on a succeeding index cycle. In the embodiment illustrated the platform 18 is pivoted to the frame as at 18a at its outer end and is spring tensioned by springs 18b to its vial receiving position illustrated in Fig. 1. The free end of the platform normally underlies the vials as they arrive at the delivery station. However, should a vial come through crosswise on the jets or for some reason be on the platform when a new bank of vials index into position, the misplaced vial will be pressed against the platform causing the latter to yield downwardly and eject the vial.

A preferred means for withdrawing the vials from the jets may comprise a vertically and horizontally movable rake member 20 that extends across the machine and supported by a movable carriage 21 at each side. The carriages are mounted on rollers 22 that are guided on movable tracks 23. Each track is pivoted as at 24 in a main frame extension 25. Vertical movement of the rake is accomplished by moving the track about its pivotal support by means of a connecting rod 26, rock lever 27 which is fulcrumed at 28, and an actuating cam 29 mounted upon the continuously driven shaft 15. The cam 29 is shaped to impart, through the linkages shown, a rising and lowering movement to the carriage track with a dwell period at the upper and the lower positions. Pull springs 30 attached to the rock lever 27 and anchored to parts of the main frame serve to maintain the lever-carried follower 31 against the operating face of the cam 29.

The means for moving the carriage along the track 23 may comprise a second rock lever 40 which is fulcrumed as at 41 to the frame. The upper end of lever 40 is pivotally secured by an elevation-compensating link 42 to the rake carriage 21, and the lower end is pivotally secured as at 43 to an adjustable connecting rod 44. Rod 44 connects at its other end with a crank-pin 45 carried, in this instance, by the track elevating cam 29. The combination of motions imparted to the rake 20 by the linkages described is somewhat rectangular, i.e., (a) Up, (off the vials), (b) In (between banks of vials), (c) Down (upon the vial necks) and (d) Out (away from the vial jets). Figure 1 illustrates the rake in an Out position just prior to lifting and releasing the vials. Four representative vials are indicated in horizontal position in the V-shaped channels provided by an extension 18c of the receiving platform 18, and the leading vial V, on each channel is approximately at the end of the extension member 18c and at rest. This stopping of the lead vials V, at the end of the extension, is adjustably controlled by adjusting the position of the pivotal connection 43 up or down in the slot 40a provided in the lower part of lever 40. When the pivot 43 is clamped relatively close to the fulcrum 41 of the lever the fixed stroke of the crank pin 45 will cause the rake to travel further than it will when the pivot 43 is adjusted and clamped in a more outward position on lever 40. And so that the adjustment in stroke of the rake effects its outward position only, the slot 40a is formed in a curve with the crank pin 45 as the center of the arc when the crank pin is in a position diametrically opposite the position shown in Figure 1. When so constructed and with the crank pin so positioned the rake will be In, and in that position, an adjustment of the pivot 43 along the slot does not change the In position of the rake because the slot 40a follows a true radius. However, as the crank revolves, the position of the pivot 43 from the pivot 41 proportionately determines the distance the rake will move outwardly. With the present invention this provision for varying the rake stroke at one end is util-

ized to bring the lead vial in each channel to the brink of the extension 18c whereupon, on the next cycle, those vials are pushed off the extension and fall upon a shelf 50 located a short distance below the extension 18c. Depending upon the length of the vials being processed the stroke of the vial rake is adjusted so that but one bank of vials is pushed off and self-oriented on the shelf 50 on each operating cycle, and the bank of vials next following are brought to rest at the brink of the extension.

Underlying the channeled extension 18c is a vial pusher carriage 51 reciprocably mounted on rollers 52 that are guided in channels 53 at each side of the machine frame. The forward face of the carriage 51 is provided with a series of pockets 50a, spaced from one another in correspondence with the spacing of the V-channels in the receiving plate 18 and its extension 18c. Normally the pockets 50a occupy a position partly under the brink of the extension 18c so that as the vials drop off the latter they fall into the pockets and are guided and maintained upright therein. The receiving pockets are effectively closed on their normally open sides by an adjustable gate member 60 that periodically is moved vertically. The gate 60 extends across all the pockets 50a in the carriage and is adjustably mounted at its ends to vertically movable guide rods 61. The rods 61 are guided by rollers 62 in vertical slots 63 in frame members 64 at each side of the machine, and their lower ends are pivotally connected to levers 65 that are mounted upon a rock shaft 66. Shaft 66 carries a third lever 67 whose free end is connected with a connecting rod 68 which in turn carries a yoke piece 69 and a cam follower 70. The follower 70 is positioned to track the surface of a gate cam 71 mounted upon the main power shaft 15. The cam is illustrated more clearly in Figure 2, and is contoured to raise and lower the gate 60 in proper timed relation with other functioning elements of the tray-loader.

Movement of the carriage 51 is brought about by means of a system of linkages including a pair of links 73 that are pivotally connected to the underside of the carriage 51 and to the upper ends of a pair of rock levers 74. Levers 74 are connected at their lower ends to a second rock shaft 75 journaled in the frame, and which is actuated by a depending lever 76. Lever 76 connects at its free end with a connecting rod 77 that in turn carries a yoke piece 78 and a cam follower 79. The follower 79 is positioned to track the face of a cam 80 mounted upon the continuously rotated power shaft 15. As illustrated more clearly in Figure 3, the carriage cam 80 is contoured to impart a reciprocatory movement to the carriage, with a relatively long dwell period in the In position, in proper timed relation with the operation of the other movable parts.

Inasmuch as the vials to be processed vary in diameter, the gate 60 is slotted horizontally at each end, as indicated at 60a and by means of a clamp screw 60b, the face of the gate may be adjusted toward or away from the carriage pockets 50a in conformity with the diameter of the vials being run.

Occasionally certain vials will tend to stick together at their ends, especially if hot and wet. Should that occur the lead vial will tend to lift a following vial before falling and to prevent this a breaker-bridge 18d is provided. The bridge 18d is vertically and horizontally adjustable and extends across all the vial channels. Preferably the bridge is formed with a downwardly bent portion 18g which functions to deflect the lead vials downwardly as they move outwardly. Any vial that may stick to the lead vial will be caused to elevate and engage the bridge and thus break the joint between the vials. The lead vial is thus separated and is free to fall into its related receiving pocket 50a. Normally the bridge is clamped in a position such that the lead vial 75 may turn from a horizontal position to a vertical posi-

tion during its fall. Up and down adjustment (for vial diameter) is obtained by adjusting bridge shelves 18e on the vertical supports 18f by means of a clamp screw and slot connection, and horizontal adjustment (for length of vial) by adjusting the bridge horizontally on the shelves 18e also by a clamp screw and slot connection provided.

The platform 50 extends beyond the gate 60 and at the proper time the gate is elevated and the pusher carriage advances and moves the partially confined vials forward along the platform 50. At the end of the carriage forward stroke the gate lowers a given amount and then the carriage recedes in preparation to receive another charge of vials. On the next following stroke the vials that were left standing unconfining on the platform 50 are engaged by the oncoming group of vials and advanced still further along the platform.

The preliminary portion of the descent of the gate 60 is utilized in this embodiment of the invention affirmatively to eject the vials from their pockets in the pusher so that they will not stick to the pockets and be carried backward. To this end the gate is provided with a cross-bar 60e that carries a series of downwardly projecting pins or needles 60d. After the vials have passed under the needles 60d the needles lower and enter recesses 50c provided in the carriage immediately behind each vial pocket. When in their partially down position the needles prevent the vials from adhering to their pockets and from being carried back with the carriage 51. After the carriage has receded beyond the gate 60 the latter lowers the remaining amount and is positioned in receiving relation with the withdrawn carriage for the next bank of vials. The two-stage lowering of the gate 60 and needle bar 60c is controlled and timed by providing cam 71 with the stepped descending portions indicated at 71a, 71b and 71c.

In accordance with this invention, the vials are caused to be channeled automatically into the open end of one or more receiving trays. In the example represented in the drawings a single tray 85 is positioned to receive the vials. This tray is closed on three sides and its bottom is arranged to underlie the platform 50. The platform 50 is preferably relatively thin particularly the portion that overlies the tray bottom so that the vials do not tip over as they are advanced from one to the other. Side guides 86 adjustably secured to the platform 50 are provided to channel the vials to the width of the open end of the tray.

The support for the tray 85 may comprise a separate stand or frame, or a frame that may be secured to the main apparatus as indicated in the drawings. As shown herein the tray support includes a top 87, an under frame 88, and one or more legs 89. The inner end of the under frame 88 is preferably secured to the main frame extensions 64 whereby the relative elevations of the top 87 and the platform 50 may be maintained at the spaced distance required to slide the bottom of the tray 85 between the two. To accommodate the sides 85a of the tray 85 (and a partition 85b if the tray is so made) the platform 50 is provided with suitable slots 50s which also serve as guide means for registering the tray with the channel guides 86. To prevent the tray from inadvertently receding as the vials are advanced a back stop 90 is provided on the top 87. The back stop in this instance comprises an angled strip, shallow enough to allow the tray to "ride over" but steep enough to offer sufficient resistance to hold the tray in place against the urge of the incoming vials. Should, however, the tray become filled and is left unattended, the pressure of the incoming vials will cause the tray to climb the back stop and ride over. In such an event means have been provided responsive to movement of the tray out of receiving position, to suspend the operation of the tray-loading mechanism and preferably also the entire machine.

A preferred form of mechanism for this purpose includes a control switch 100 electrically connected with the starter switch of the motor that drives the power shaft 15. A control circuit diagram is illustrated schematically in Figure 6. The tray switch 100 is provided with a yieldable roller 101 that is positioned to engage the leading end of the tray and which when depressed by a tray inserted between platform 50 and stand top 85, closes a portion of the circuit to the main drive motor. When this switch 100 is closed, the motor may be operated to drive the shaft 15. If a tray is not present, or if present, is caused to shift rearwardly a predetermined amount, the switch roller 101 lifts slightly and opens the circuit. In the washing machine organization illustrated in part herein, the main drive motor M operates a cam 150 that actuates a cycle switch 161 connected across the starting circuit so that the machine is caused to cease functioning at the completion of a washing cycle at which time the processing valves have been actuated to closed position and the processing fluids shut off.

It will also be seen that the tray switch 100 operates to stop the machine when a filled tray is removed and about to be replaced by an empty tray. During the interval required to change trays, the machine is at rest and no vials are being advanced along the platform 50.

Preferably, the platform 50 is caused to overlap the leading end of a tray a distance sufficient to accommodate a full complement of vials advanced by a forward stroke of carriage 51, so that when it is time to remove a filled tray adequate space remains in that covered portion of the tray to receive the vials that are advancing on that cycle and such other vials as may have been advanced partly off the platform 50 at the time the machine cycle stops.

35

Operation

The operation of the vial removing and loading mechanism is as follows: Assuming that the jets of the washing machine have been supplied with vials, a first bank of vials will arrive at the delivery station and lie horizontally in the channels of the platform 18. The rake 20 will thereupon advance in an elevated position and gradually descend upon the necks of the vials. When fully seated the crank pin 45 will have passed dead center and through the connecting rod 44, lever 40, link 42 and carriage 21 will move outwardly and draw the vials off the jets. This operation repeats itself until the extension platform 18a is filled with rows of abutting vials and on the next cycle the vials at the brink of the platform are pushed off the platform 18a and fall right end up upon the lower platform 50. At this point in the operational cycle, the pusher carriage 51 is in its In position, the gate 60 is down and the vials are confined in orderly arrangement by the pockets 51a and the face of the gate 60. Thereafter the gate elevates in response to the action of cam 71 to a position whereat the vials may pass beneath. At this time the pusher carriage 51 advances in response to its cam 80, and the partially confined vials are moved along the platform 50. When the carriage cam 80 reaches its maximum throw position with relation to the follower 79, forward movement of the vials ceases, the gate lowers a preliminary amount to eject the vials, and the carriage is retracted by the force of pull springs 74a connected to lever 74 and a stationary part of the machine. When the carriage has cleared the gate and is retracting, the gate completes its down movement by gravity assisted by the force of pull springs 67a connected with lever 67, under the control of the cam 71. As the gate arrives in its down position another bank of vials is about to be oriented by falling into the pockets 51a and on the ensuing cycle of the gate and pusher carriage another bank of vials are advanced along the platform and brought into engagement with the previous bank of free-standing vials. The latter are accordingly advanced still further and in doing so assume a varied pattern. As the machine continues to cycle in this manner, successive

banks of vials are unloaded from the jets, oriented and advanced along the platform 50 and find their way in mixed fashion between the side guides 86 to the open end of the tray 85. When the tray has been filled, the operator replaces the filled tray with an empty one, the machine being automatically stopped during the interval the leading end of a tray remains off the switch actuating roller 101.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention, and therefore, such adaptations should be, and are intended to be comprehended within the meaning and range of equivalency of the following claims.

Having thus revealed this invention, I claim as new and desire to secure the following combinations and elements, or equivalents thereof, by Letters Patent of the United States:

1. In a machine of the character described operative cyclically to deliver banks of vials in horizontal position successively to a delivery station, said machine having a main drive shaft to govern the delivery cycle, the combination of a support adapted to receive the vials at the delivery station, a reciprocable rake element and operative connections with the main drive shaft of the machine for moving successive banks of vials away from the delivery station and advancing them in horizontal position along said support, a receiving platform positioned at the end of said support and in a plane sufficiently below the plane of said support so that on each outward stroke of the rake a bank of vials is caused to fall from the support upon said receiving platform in an upright position, and means operatively connected with and actuated from the main drive shaft of the machine for successively moving the banks of upstanding vials along the platform away from said support in timed relation with the operation of said rake element.

2. The combination of claim 1 in which said rake operating means includes means for adjusting the outward terminus of the stroke of the rake to accommodate vials of a selected size so that but one bank of the vials is caused to reach the end of the support and fall to the receiving platform on each operating stroke of the rake.

3. The combination of claim 2 in which the length of the support is greater than the stroke of the rake by at least one vial length.

4. In a machine of the character described operative cyclically to deliver banks of vials to a delivery station in horizontal position the combination of a support of a prescribed length at the delivery station for receiving the vials, a drive shaft driven in timed relation with the operational cycle of the machine, a reciprocable rake element operable from said drive shaft for moving banks of vials successively away from the delivery station and for advancing them in horizontal position along said support of prescribed length, a receiving platform positioned at the end of said support and in a plane sufficiently below the plane of said support so that on each outward stroke of the rake a bank of vials is caused to fall from the support upon said receiving platform with the vials in upright position, a normally stationary but movable gate element spaced from the end of said support a distance sufficient to provide space to receive the upstanding vials, vial pusher means also actuated from said drive shaft for moving the banks of upstanding vials successively along the platform away from the end of said support in timed relation with the operation of said rake element, and means also actuated from said drive shaft for actuating said gate element to and from vial receiving position in timed relation with the operation of said vial pusher means.

5. The combination of claim 4 including means cooperatively related to said pusher element and operative at the end of the forward stroke of the pusher for retaining the vials in the position to which they have been moved by said pusher element.

6. The combination of claim 4 in which said vial receiving support comprises a pivotally mounted section and a normally stationary section, and spring means connected with the pivotally mounted section operative to retain the said section yieldingly in vial receiving position.

7. The combination of claim 4 including a bridge element overlying said support and positioned adjacent the end thereof adapted to be engaged by the vials and separate the vials that are about to fall from those that remain on the support.

8. In a machine arranged to transport vials from a processing station to a delivery station and to position the vials in a horizontal position at the delivery station, the combination of a normally horizontally disposed vial receiving platform mounted for pivotal movement at the delivery station, a horizontally reciprocable rake member and means connected therewith for actuating the rake to a position of engagement with the vials on the vial-receiving platform to a position laterally removed from the delivery station, a second horizontally disposed vial-receiving platform positioned at the end of the first named platform, said rake member having an effective stroke such that the vials are caused to be brought successively off the first receiving platform and onto said

20 second receiving platform, a third receiving platform positioned below the second receiving platform a distance sufficient to permit the respective vials to revolve in space to an upstanding position on to the third platform as they are caused to fall from the end of the second platform, vial-push means for moving the standing vials along the third platform, and operative connections between said vial-push means and the machine for actuating the vial-push means cyclically in timed relation with the operation of said rake member.

40 9. In a machine of the character described operative cyclically to deliver vials in a horizontal position at a delivery station on the machine the combination of a vial receiving platform at the delivery station, a horizontally reciprocable rake member overlying the receiving platform, means for actuating the rake member cyclically to a position of engagement with the vials at the delivery station to a position laterally removed therefrom, a second vial-receiving platform positioned at the end of the first named platform and in a plane below the plane of

45 the said first named platform, said rake member actuating means being operative to actuate the rake through a fixed stroke such that the vials are caused to be brought thereby successively to the end of the first receiving platform and caused to fall therefrom onto said second receiving platform, an open ended receiving tray positioned on said last named receiving platform for containing the vials in upstanding position, and a reciprocable pusher element operatively located in the space between the said platforms for advancing the vials into the open end of the receiving tray, and means connected with said pusher element for reciprocating the pusher in timed relation to the operation of the rake member.

50 10. In a machine of the character described in which banks of vials arrive at a delivery station in horizontal position, a vial-removing and vial orienting mechanism combining a main drive shaft and means connected therewith for actuating the machine intermittently, a support adapted to receive the vials at the delivery station, a reciprocable rake element operated from said drive shaft for moving the successive bank of vials from the delivery station and advancing them in horizontal position along said support, a receiving platform positioned at the end of said support and in a plane sufficiently below the plane of said support so that on each outward stroke of the

75 said rake a bank of vials is caused to fall from the sup-

port upon said receiving platform in an upright position, means also actuated from said drive shaft for successively moving the banks of upstanding vials along the platform away from said support in timed relation with the operation of said rake element, a tray member mounted on said platform adapted to receive the upstanding vials, and safety means responsive to the presence of a tray on said support in vial receiving position for rendering the drive shaft operative.
